LOOM FLAG

John B. Sherrill, Drawer 578, Gastonia, N.C.

Filed July 2, 1965, Ser. No. 86,017

Term of patent 3½ years

(Cl. D72—1)

FIG. 1

FIG. 2

FIGURE 2 is a fragmentary elevation looking at the back wall of the base with the lower portion of the base and the staffs of the flags omitted;

The side of the loom flag not shown is like the side shown in FIGURE 3.

I claim:

The ornamental design for a loom flag, substantially as shown.
